UNITED STATES PATENT OFFICE.

WILLIS H. AKIN, OF FALCONER, NEW YORK, ASSIGNOR OF ONE-FOURTH TO CHARLES F. MOYER AND ONE-FOURTH TO ADOLPHUS J. BATEMAN, BOTH OF FALCONER, NEW YORK.

FILM-REWINDING MECHANISM.

1,156,025.

Specification of Letters Patent.

Patented Oct. 5, 1915.

Application filed July 21, 1915. Serial No. 41,090.

To all whom it may concern:

Be it known that I, WILLIS H. AKIN, a citizen of the United States, residing at the village of Falconer, in the county of Chautauqua and State of New York, have invented certain new and useful Improvements in Film-Rewinding Mechanism, of which the following, taken in connection with the accompanying drawings, is a specification.

The invention relates to film reeling mechanism for moving picture machines and the object of the improvement is to provide a simple mechanism for reversing one film by rewinding while another film is being unreeled, the reels being so arranged that a single operator can control both the unreeling and rereeling without moving from his position in front of the machine, provision being made for the care of the films by the operator in case of breakage so that the re-winding film may be cared for without endangering the same while the unreeling film is joined, both films being protected from danger of ignition by fire since they are highly combustible; and the invention consists in the novel features and combinations hereinafter set forth and claimed.

In the drawings, Figure 1 is a front elevation of the moving picture machine with the improved rewinding cabinet on the underside of the table, the doors of said cabinet being open and showing the arrangement of the rewinding mechanism therein with the film reels in position. Fig. 2 is a sectional view at line X-X in Fig. 1 showing the construction and arrangement of the double length spindle or shaft which is revolvably mounted in the rewinding cabinet and is shown with the two reels in position thereon, said spindle having a pulley thereon which is connected by belt to the crank shaft of the moving picture machine so that the operator turns said pulley and spindle when turning the crank of the moving picture machine. Fig. 3 is a perspective view of the separator sleeve for holding the film reels a spaced distance apart on the long spindle. Fig. 4 is a perspective view of the locking spring for the rewinding reel on the long spindle. Fig. 5 is a perspective view of the rewinding cabinet with the doors open showing the spindles in position. Fig. 6 is an elevation of the rear side of the moving picture

machine with the rewind cabinet attached to 55 the supporting table, showing the pulley and belt connection between the rewinding spindle and the operating shaft of the moving picture machine. Fig. 7 is an elevation of the long spindle.

Like numerals of reference refer to corresponding parts in the several views.

The moving picture machine comprises the bench or table 10 which supports the moving picture projecting machine case 11 65 at one end and the lamp house at the other. The case 11 has the reel cabinet 12 thereon into which the film reel 13 is placed when it is desired to project the same through the moving picture machine 11.

The door 14 of the cabinet 12 is provided on its inner side with a cap 15 which engages over the end of the spindle 16 for the reel 13, the cap 15 being supported on the end of a spring 17 thereby holding the reel 13 as a 75 resilient tension brake to prevent too rapid unreeling.

The film 18 extends from the reel 13 over a roller 19 on the machine 11 and down through a slot 20 in the top of the film cabinet 21. A guide roller 22 is placed over the slot 20 to hold the film 18 firmly in line as it passes down through the slot 20 to the lower reel 23.

The reel 23 is mounted on and revolves 85 with the spindle 24 in line with the moving picture machine 11 and reel 13. Said spindle 24 is revolvably mounted in the rear wall 25 of a cabinet 21, extending to the rear of the cabinet to receive thereon the split pulley 26, a spring 27 being provided on the rear end of the spindle 24 to resiliently hold the split pulley 26 in place. The pulley 26 is a resiliently held split pulley so that when the film 18 sticks, the parts of the split pulley will spring apart, the belt drawing in between said parts thereby relieving the strain on the films 18 and preventing its breakage. The spindle 24 has a shoulder 28 which bears against the said wall of the 100 cabinet 25 to thereby hold the spindle 24 in position and against endwise movement. The spindle 24 is made double length to receive the two reels 23 and 29 thereon, and a separator sleeve 30 is placed between the two 105 reels 23 and 29 and held in place on the spindle 24 by means of a set screw.

The outer reel 29 is held in place on the

spindle 24 by means of a spring locking clip 31 which has the open ended tapered slot 32 in one end and is bowed so that it slides over the end of the spindle 24 in the annular 5 groove 33 and presses against the reel 29 at both ends. The upper end of the spring clip 31 is turned outwardly to form a holding means for the insertion and withdrawal of said clip. It is apparent that this gives a 10 firm yet resilient holding for the reel 29 causing it to normally turn with the spindle 24 within the cabinet 21, and to turn on the spindle 24 under abnormal strain.

The cabinet 21 is preferably constructed 15 with two compartments 34 and 35 which are connected to one another and has doors 36 for the compartment 34 and 37 for the compartment 35, each of the doors preferably having glass panels 38 so that the operator 20 sitting in front of the cabinet can always direct the process of rewinding as well as the winding of the film 18 on inner reel 23. The compartment 34 is made about double the depth of the compartment 35 in order 25 to receive the two reels 23 and 29 therein on the long revolving spindle 24. A fixed spindle 39 is provided about central of the rear wall 35 to receive thereon the reel 40 from which it is desired to rewind the film 47 onto 30 the reel 29. A spring tension cap 41 is provided for the end of the spindle 39, which cap is supported on a spring 42 attached to the frame of the door 36 so that the cap bears against the reel 40 with the desired 35 tension pressure.

A spindle 43 is provided midway between the reels 29 and 40 and extending out from the rear wall and having thereon an idler roller 44 over which the film rolls in re- 40 winding thereby omitting manual guidance and contact and keeping said film flat and always in line as it passes from one reel to the other. In order to provide means for holding the reel 29 when the film 18 breaks 45 as it runs from the reel 13 to the reel 23, as sometimes happens, a spindle 45 is hinged on the bottom of the cabinet 21 to fold within the same alongside of the semi-partition 46, so that said spindle 45 can be turned 50 outward and the reel 29 may be placed thereon without removing the film from over the idler roller 44 thereby permitting access to the inner reel 23 for the repair of the film 18, after which the reel 29 may be re- 55 placed upon the spindle 24 and the process of projecting the pictures through the moving picture machine 11 in combination with the rewinding of the film 47 can proceed.

It is of course understood that all reels 60 after projection have to be reversed by re-winding. By my arrangement the projection of the film 18 can be attained by the operator simultaneously with the rewinding of the film 47 without extra exertion or soil- 65 ing manual contact, both operations being

within the control of the single operator and in nowise hindering the projection of the pictures from the film 18.

When it is desired to operate the machine, the reel 13 is placed in the cabinet 12 and the film 18 is passed over the rollers 19 and 22 and through the slot 20 and connected to the reel 23. The separator sleeve 30 is then placed on the spindle 24, and the reel 40 with the film 47 to be rewound is placed on the 75 spindle 39 and the film 47 is connected to the empty reel 29. The operator then turns the crank 48, or it is turned mechanically, thereby turning the shaft 49 and causing the belt 50 to turn the pulleys 51 and 25 and 80 spindle 24, thereby rotating the reels 23 and 29 and simultaneously unwinding the film 18 and rewinding the film 47, both operations being within the vision and reach of the single operator, the operation of rewinding or arrangement of the reels 29 and 40 being easy of attainment by the unoccupied hand of the operator even when he is turning the crank 48.

The doors 36 and 37 of the rewinding 90 cabinet 21 are preferably made dust proof by means of a strip 52 of felt or other suitable packing around the inner edges of said doors to thereby shut out all dust and grit from said cabinet and particularly during 95 the rewinding operation to thereby prevent the scratching or otherwise marring of the films 18 and 47, thereby greatly prolonging the life and increasing the value of said films.

It is also obvious that no handling of the films 18 and 47 is necessary in rewinding or unreeling of the same. Consequently, all danger of marring or deterioration through 105 said handling is overcome by my rewinding cabinet. The operation is fully under the eye of the operator while rewinding and unreeling while the doors are closed thereby preventing all accumulations of dust and 110 shut out anything that would mar or otherwise injure said films during the rapid revolution of said reels in rewinding the same.

I claim as new:

1. In combination with a moving picture machine, film rewinding mechanism comprising a double length rotatable spindle to removably receive one of the film reels of said moving picture machine thereon and to removably receive a second rewinding film reel thereon in front of said film reel of said moving picture machine, a pulley on the rear end of said double length spindle behind both of said film reels for rotating said spindle and film reels, a fixed spindle a spaced distance from said double length spindle to rotatably support a third film reel in line with the front film reel on said double length spindle, said third film reel on said fixed spindle containing the film to be rewound; and belt connection between 120 125 130

said pulley on said double length spindle and said moving picture machine to simultaneously rotate said double length spindle and operate said moving picture machine 5 and rewind said film to be rewound upon said front film reel.

2. In combination with a moving picture machine, a film rewinding cabinet, a double length rotatable spindle in said cabinet to 10 removably receive one of the film reels of said moving picture machine thereon and to removably receive a second rewinding film reel thereon, means for turning said double length rotatable spindle by the operation 15 of said moving picture machine, a fixed spindle a spaced distance from said double length spindle to support a third rewinding film reel thereon in line with said second rewinding film reel, and a third spindle 20 hingingly attached in said rewinding cabinet to fold within said cabinet when the doors are closed and to receive said second rewinding film reel thereon when either of the films are in trouble.

25 3. In combination with a moving picture machine, a cabinet supported beneath said moving picture machine and opening toward the operating side of said moving picture machine, a double length spindle rotatably 30 mounted in said cabinet to receive one of the film reels of said moving picture machine on the inner end thereof and a second film reel on the outer end thereof, a pulley 35 on the rear end of said double length spindle, a belt connecting said pulley to the operating shaft of said moving picture machine to simultaneously turn said spindle and the reels thereon with said operating shaft of said moving picture machine, a 40 fixed spindle in said cabinet a spaced distance from said double length spindle to rotatably support a third film reel thereon in line with said second film reel, a spring cap for said fixed spindle to bear against 45 said third film reel and give tension thereto,

and a roller midway between said second and third film reels to pass the film to be rewound thereover from said third reel to said second reel.

4. In combination with a moving picture 50 machine, a rewinding cabinet comprising two compartments, doors for said compartments opening toward the operating side of the machine having glass therein, a double length spindle mounted in one of said compartments 55 to receive one of the film reels of said moving picture machine on the inner end thereof and a second rewinding film reel on the outer end thereof, said double length spindle extending through the rear wall of said cabinet and rotatively mounted therein, a split pulley on the outer rear end of said spindle and a spring on said spindle to resiliently hold said split pulley, said split pulley belted to the operating shaft of said 60 moving picture machine to be simultaneously turned with said operating shaft, a sleeve keyed between said inner and outer film reels on said double length spindle to hold said reels a spaced distance apart, a 65 spring holding clip to hold said second film reel on the outer end of said double length spindle, a fixed spindle in the other compartment of said rewinding cabinet a spaced distance from said double length spindle to 70 rotatably receive thereon a third film reel in line with said rewinding film reel on said double length spindle, a spring having a cap on one end and attached at the other end to the door of the compartment to engage over 75 said fixed spindle when the door is closed and press against said third film reel and give tension thereto.

In testimony whereof I have affixed my signature in the presence of two witnesses. 80
